US0D1090452S

(12) **United States Design Patent** (10) **Patent No.:** **US D1,090,452 S**
(45) **Date of Patent:** **** Aug. 26, 2025**

(54) **POWER STRIP**

(71) Applicant: **SHENZHEN ORICO TECHNOLOGIES CO., LTD.,**
Shenzhen (CN)

(72) Inventors: **Yeyou Xu**, Shenzhen (CN); **Chuanxin Mao**, Shenzhen (CN)

(73) Assignee: **SHENZHEN ORICO TECHNOLOGIES CO., LTD.,**
Shenzhen (CN)

(**) Term: **15 Years**

(21) Appl. No.: **29/918,386**

(22) Filed: **Nov. 28, 2023**

(51) LOC (15) Cl. **13-03**

(52) U.S. Cl. **D13/137.2**

(57) **CLAIM**

The ornamental design for a power strip, as shown and described.

DESCRIPTION

FIG. 1 is a front, right and bottom perspective view of a power strip showing our new design;

FIG. 2 is a rear, left and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict the portions of the power strip that form no part of the claimed design.

1 Claim, 8 Drawing Sheets
